UNITED STATES PATENT OFFICE.

WILLIAM P. SEIBERT, OF ALLEGHENY, PENNSYLVANIA, ASSIGNOR TO THE STANDARD MANUFACTURING COMPANY, OF SAME PLACE.

DESIGN FOR A BATH-TUB.

SPECIFICATION forming part of Design No. 27,488, registered August 3, 1897.

Application filed March 13, 1897. Serial No. 627,428. Term of patent 14 years.

To all whom it may concern:

Be it known that I, WILLIAM P. SEIBERT, a citizen of the United States, residing at Allegheny city, in the county of Allegheny and State of Pennsylvania, have invented a Design for Bath-Tubs; and I do hereby declare the following to be a full, clear, and exact description of the invention, such as will enable others skilled in the art to which it appertains to make and use the same.

My invention has relation to designs for bath-tubs; and it consists in a tub of the pattern herein described and illustrated.

In the accompanying drawings, Figure 1 is a plan view of a tub embodying my design. Fig. 2 is a side elevation. Fig. 3 is an end view, and Fig. 4 a transverse section.

The tub A is oblong with a rounded inclined front end or head B, a nearly vertical rear end, and converging side walls C, an in-

clined hollow bottom D, the inclination being from the front and to the rear end and the shape of the bottom being that of a section or segment of a cone. The side walls are joined to the front and rear walls on curves 25 and the sides are joined to the bottom by rounded corners e e. The axes of the rounded corners e e are parallel with the floor line or rim of the tub and the legs or supports f f are of equal lengths. The configuration of 30 the legs is not an essential part of my design.

What I claim as new is—

The design for a bath-tub as herein shown and described.

In testimony whereof I affix my signature 35 in presence of two witnesses.

WILLIAM P. SEIBERT.
